CLAIM

The ornamental design for a button, as shown and described.

DESCRIPTION

FIG. 1 is a top perspective view of a button showing my new design;

FIG. 2 is a bottom perspective view thereof;

FIG. 3 is a top plan view thereof;

FIG. 4 is a bottom plan view thereof;

FIG. 5 is a right side elevation thereof;

FIG. 6 is a left side elevation thereof;

FIG. 7 is an upper side elevation thereof;

FIG. 8 is a lower side elevation thereof;

FIG. 9 is a sectional view taken along line 9—9 in FIG. 4;

FIG. 10 is a sectional view taken along line 10—10 in FIG. 4;

FIG. 11 is a sectional view taken along line 11—11 in FIG. 4;

FIG. 12 is an exploded view in perspective thereof showing the two sections of the button separated; and FIG. 13 is also an exploded view in perspective showing the two sections of the button separated and the clip removed.
